Attorney.

UNITED STATES PATENT OFFICE.

CHARLES W. McDANIEL, OF LAKE VILLAGE, NEW HAMPSHIRE, ASSIGNOR
OF ONE-HALF TO JOSEPH A. BURLEIGH, OF SAME PLACE.

FURNACE-MOUTH.

SPECIFICATION forming part of Letters Patent No. 461,504, dated October 20, 1891.

Application filed June 22, 1891. Serial No. 397,092. (No model.)

To all whom it may concern:

Be it known that I, CHARLES W. McDANIEL, a citizen of the United States, residing at Lake Village, in the county of Belknap and State of New Hampshire, have invented certain new and useful Improvements in Furnace-Mouths, of which the following is a specification.

This invention relates to a furnace-mouth having a casing to protect it from being burned out by the heat of the fire, and in which water may be heated for feeding the boiler or for other purposes.

The objects of the invention are to provide a complete protection to the entire inner face of the furnace-mouth where it is exposed to the injurious effects of the fire, and secure a thorough and continuous circulation of water through said mouth.

The invention consists in a furnace-mouth provided with a casing covering the entire inner face of the sides and top of said mouth, said casing being divided into connected superposed water-jackets, which form a continuous water-course for the circulation of water, substantially as hereinafter set forth.

In the accompanying drawings, Figure 1 represents a furnace provided with this improved furnace-mouth and surmounted by an upright steam-boiler. Fig. 2 represents a vertical longitudinal section of this improved furnace-mouth in which the tortuous channels are so arranged as to form a triple water-jacket.

Similar numerals of reference indicate corresponding parts in the different figures.

This improvement is represented in the drawings in connection with a steam-boiler furnace 10 for an upright steam-boiler 11; but it may be used in connection with furnaces for horizontal steam-boilers or other furnaces.

This improved furnace-mouth comprises an inverted-U-shaped casing 20, composed of cast, sheet, or wrought metal, said casing extending up the sides and over the top of the furnace-mouth, its lower ends resting on the bottom of said mouth. The casing is preferably rectangular in cross-section and of a depth equal to the depth of the furnace-mouth. The interior of this casing is divided by internal partitions into tortuous channels,

forming a single continuous water-course. These partitions are disposed longitudinally of the casing 20 parallel with the inner and outer walls thereof. The inner interior partition 21 extends from the bottom of the right-hand leg of the casing up through said leg, over through the top of the casing, and down through the left-hand leg thereof, terminating above the bottom of said left-hand leg. The outer interior partition 22 extends from the bottom of the left-hand leg of the casing up through said leg, over through the top of the casing, and down through the right-hand leg, terminating above the bottom thereof. These partitions thus form three superposed water-jackets, each of a width equal to the depth of the furnace-mouth, and so connected as to form a continuous water-course, each succeeding jacket being slightly longer than the preceding, so that the water has room to expand as it becomes heated.

An inlet-pipe 30 is connected to one end of the continuous water-course formed by the series of connected channels, and an outlet-pipe 40 is connected to the other end thereof, the inlet of pipe 30 being shown in Fig. 2 as disposed at the bottom of the right-hand leg of the casing between the inner wall thereof and the inner interior partition 21, and the outlet-pipe as connected to the left-hand leg of the casing near the bottom thereof between its outer wall and the outer interior partition 22. The inlet-pipe is provided with a cock 31. This pipe may lead from a tank, a street-main, or any other source of water-supply.

The outlet-pipe 40 is provided with a faucet 41, or said pipe may lead to any desired point where the hot water may be utilized.

A pipe 42 connects the outlet-pipe 40 with the top of the steam-boiler, and a pipe 43 connects said pipe 42 with the top part of the casing constituting the furnace-mouth. This pipe 43 is provided with a safety-valve 44, and in case the supply-pipe 30 and outlet-pipe 40 be closed and steam be generated in the casing the pressure thereof will be relieved through said safety-valve.

The arrangement of the superposed water-jackets in a continuous water-course insures a uniform current or circulation of water

through the protector or casing, avoids eddies and dead water at any part thereof, affords room for the expansion of the heated water in each succeeding water-jacket, and, owing to the cooling effect of one jacket upon another, tends to prevent the formation of steam in the casing.

I claim—

10 A lining for a furnace-mouth, consisting of an inverted-U-shaped casing covering the side walls and top thereof, said casing being provided with inlet and outlet pipes and with

an internal partition or partitions forming connected superposed water-jackets constituting a continuous water-course, substantially as described.

In testimony that I claim the invention above set forth I affix my signature in presence of two witnesses.

CHARLES W. McDANIEL.
